A. M. BAROODY

MILK BOTTLE CLOSURE

Filed Feb. 25, 1922

Inventor
Assad M. Baroody

By *Frank C. Spangler*

Attorney

UNITED STATES PATENT OFFICE.

ASSAD M. BAROODY, OF DANVILLE, VIRGINIA.

MILK-BOTTLE CLOSURE.

Application filed February 25, 1922. Serial No. 539,210.

To all whom it may concern:

Be it known that I, ASSAD M. BAROODY, a citizen of the United States, residing at Danville, in the county of Pittsylvania, State of Virginia, have invented certain new and useful Improvements in Milk-Bottle Closures; and I do hereby declare the following to be a full, clear, and exact description of the invention, such as will enable others skilled in the art to which it appertains to make and use the same.

This invention relates to new and useful improvements in closures and particularly to milk bottle closures.

One object of the invention is to provide a disk closure for a milk bottle which is adapted to bend across a transverse line so that a portion of the disk can be bent out to provide an opening for pouring the contents of the bottle, and moving means therefor.

Another object of the invention is to provide a closure disk of this character having a novel and improved finger grip, which is adapted to be grasped to swing the hinged part of the disk into open position, and which finger grip normally lies flatly against the face of the disk, to permit the disks to be stacked.

A further object is to provide a finger loop, hinged to the disk, and which is so attached that it will not readily be pulled or torn from the disk.

A still further object is to provide a finger grip for a bottle closure of this character, which is hinged or pivoted to the movable or hinged section of the disk.

Other objects and advantages will be apparent from the following description when taken in connection with the accompanying drawing.

In the drawing:

Figure 1 is an enlarged top plan view of the disk with the finger grip lying flatly against the face thereof.

Figure 2 is an enlarged transverse sectional view on the line 2-2 of Figure 1.

Figure 3 is an enlarged transverse sectional view on the line 3-3 of Figure 1.

Figure 4 is a plan view of a modified form of the disk.

Figure 5 is a sectional view on the line 5-5 of Figure 4.

Figure 6 is a sectional view on the same line as that of Figure 5 showing the movable part of the disk swung upwardly.

Referring particularly to the accompanying drawing 10 represents the disk closure which is formed from heavy paper, pasteboard or the like, and which is adapted to be snapped into the mouth of a milk bottle. On the lower face of the disk, and transversely thereof is formed a score or cut 12, which permits one portion, that is one-half or less, of the disk, to be bent into the position shown in Figure 1, so that the liquid may be readily poured from the bottle.

In the movable portion of the disk, designated as 10', near the edge thereof, and parallel to the score line 12, a wire staple 13 has its ends disposed in penetrating relation through the disk and then bent laterally against the lower face of the disk, as shown at 14. A wire loop 15, has the ends of its legs bent into hook form as shown at 16, and with the bills engaged beneath the end portions of the portion of the staple 13, which lies against the upper face of the disk. The remaining portion of the loop extends inwardly in the direction of the score line 12, and lies flatly against the upper face of the movable portion 10' of the disk. In the application of the loop to the staple, these leg ends 16 will be pressed very tightly in embracing engagement with the staple.

To open the bottle, to permit the contents to be poured therefrom, the finger nail is engaged under the bight of the loop so that it may be raised from the disk after which the operator grasps the loop between the forefinger and thumb and swings the loop upwardly on the staple 13. Then by an upward pull on the loop, and with the thumb or finger of the other hand resting on the other portion of the disk, the portion 10' of the disk may be swung upwardly to provide an opening through which the contents of the bottle may be poured. The portion 10' may then be swung down and snapped into the mouth of the bottle so that the contents will be effectively prevented from escape and dirt or dust excluded from the contents.

In Figures 4, 5 and 6 there is shown a modified form of the disk, particularly with reference to the hinging connection between the two portions. The portions of the disk are indicated by the numerals 17 and 18. The disk is cut transversely from its opposite edges on a line parallel with the diameter thereof, as indicated at 19, the cuts being parallel in the upper and lower faces of the disk but spaced from each other. The

cuts extend inwardly toward the center of the disk and terminate a suitable distance at each side thereof. From the inner ends of the cuts 19 there are made shorter cuts at right angles thereto, indicated at 20, these cuts being also made in the same manner as the cuts 19, so that when the movable section 17 is bent along the lines 19, the portions of the fibre of the disk will break between the upper and lower lines of the cut to form ledges, whereby when the movable section is again swung downwardly into the plane of the other section, there will be provided a joint which will prevent escape of the liquid or ingress of dust or dirt.

Between the outer ends of the cuts 20, and on the inner face of the disk, there is formed a score 21, so that the disk will bend along this line. This forms the hinge on which the section 17 is arranged to swing. The section 17 is provided with a finger grip 22 similar to that shown in the first form.

What is claimed is—

1. A bottle closure comprising a disk having its opposite faces formed with cuts extending from opposite edges of the disk parallel to the diameter of the disk and extended at right angles into parallel relation at their inner ends, the cuts of one face of the disk being offset with respect to the cuts of the other face with resultant interlocking ledges when the material of the disk between the cuts of the opposite faces is broken.

2. A bottle closure comprising a disk hav-

ing a relatively stationary portion and a relatively movable portion, the abutting edges of said portions being formed with ledges one of which is directed toward one face of the section and the other directed toward the other face of the other section said abutting edges being approximately L-shaped with corresponding portions in alignment and in parallel relation respectively, the disk being scored on one face at right angles to and between the outer ends of the parallel portions of the said cuts, the said ledges being so arranged that the material of the disk of the movable section will snap past the material of the other section when the said movable section is moved out of the plane of the other section.

3. A bottle closure comprising a disk having transverse cuts on its opposite faces which are offset but parallel to each other, the material between the cuts of the opposite faces being adapted to be broken when one portion of the disk is moved out of the plane of the disk resulting in ribs, one of which is arranged to snap past the other when the said portion is moved out of the plane of the disk.

In testimony whereof, I affix my signature, in the presence of two witnesses.

ASSAD M. BAROODY.
